US0D1017822S

(12) **United States Design Patent** (10) **Patent No.:** **US D1,017,822 S**
(45) **Date of Patent:** **** Mar. 12, 2024**

(54) **SKIN TONING DEVICE**

(71) Applicant: **Carol Cole Company**, Vista, CA (US)

CA 2363383 5/2003
CN 102159151 8/2011

(72) Inventor: **Tera Peterson**, Carlsbad, CA (US)

(Continued)

(73) Assignee: **Carol Cole Company**, Vista, CA (US)

(**) Term: **15 Years**

(21) Appl. No.: **29/865,089**

(22) Filed: **Jul. 7, 2022**

(57) **CLAIM**

The ornamental design for a skin toning device, as shown and described.

DESCRIPTION

FIG. 1 is a front perspective view of an embodiment of a body of a skin toning device;

FIG. 2 is a rear perspective view of the body shown in FIG. 1;

FIG. 3 is a front elevational view of the body shown in FIG. 1;

FIG. 4 is a rear elevational view of the body shown in FIG. 1;

FIG. 5 is a right side elevational view of the body shown in FIG. 1;

FIG. 6 is a left side elevational view of the body shown in FIG. 1;

FIG. 7 is a top plan view of the body shown in FIG. 1; and, FIG. 8 is a bottom plan view of the body shown in FIG. 1. The broken lines shown in the drawings are for the purpose of illustrating portions of the skin toning device, which form no part of the claimed design.

1 Claim, 8 Drawing Sheets
